UNITED STATES PATENT OFFICE.

LUDOMIR KORCZYNSKI, OF CRACOW, POLAND.

SPARKING PLUG.

Application filed July 18, 1922. Serial No. 575,790.

To all whom it may concern:

Be it known that I, LUDOMIR KORCZYNSKI, a citizen of Poland, residing at Cracow, Poland, have invented certain new and useful Improvements in Sparking Plugs, of which the following is a specification.

My invention has reference to sparking plugs for the ignition of the gas mixture in explosion engines or internal combustion engines by means of an electric spark passing between two electrodes, and it is intended to avoid and dispense with the drawbacks and difficulties of spark plugs and the like, as heretofore constructed, and to generally improve the mode of operation and construction of devices of this kind.

In the sparkers and spark plugs as heretofore constructed one of the greatest inconveniences is the fact that oil and combustion residues resulting in a failure of the ignition are deposited particularly at the electrodes, and especially in the case of an abundant admission of fuel. Then there is the drawback of the sometimes very objectionable manner of securing the sparkers to the insulating body, the difficulty of cleaning the parts and the impossibility of adjusting the relative distance of the electrodes which facilitates the cranking of the motor.

A spark plug embodying the feature of my invention, is shown by way of example upon the accompanying drawing in longitudinal sectional view.

The outer fitting 2 of ordinary size is provided at its upper portion with the usual six-cornered nut portion 2^a for the engagement of a wrench or the like, and at its lower portion it is provided with the threaded portion 2^b adapted to be threadedly fitted in the wall of the motor cylinder, and provided at its bottom with the two projections 2^c between which the electrode 9 is secured, the middle portion 9^a of which may, for instance, be of globular shape.

The interior insulation of the sparking plug is provided for by two socket pieces 8 and 15 of porcelain or the like which are secured in the fitting 2 by the threaded annulus 1. At the points of pressure the usual washers 3, 4, 5 and 6 of mica, asbestos or the like are provided. In the interior of the socket 15 an interiorly threaded tube 12 is secured by means of a nut 13, a flange 12^a being provided at the lower end of the tube 12. By the tightening of the

threaded annulus 1, the sockets of porcelain or the like are only submitted to pressure strain, but at the exclusion of shearing stress so that there is no danger of bursting of said sockets. The current is admitted in the usual manner, by means of a cable which is screw-threadedly secured between the nuts 13 and 14.

In the interior of the tube 12 another tube 11 is threadedly secured, at the top of which there is a notch 11^a, for the screw-driver, and is otherwise somewhat funnel-shaped in order to facilitate the pouring in of benzene and the like, if desired. The lower portion of the said tube serves as a guide for the stem 10^a of a movable valve electrode 10, the lower end of the tube serving as a valve seat. The electrode 10, the stem 10^a of which is of four cornered cross section, in order to provide for the passage of air, is provided with a small reduced portion 10^b, and below this part there is the semi-globular valve body proper 10^c, and the plate shaped enlargement 10^d. The lower end 10^a of substantially hyperboloid shape constitutes the second electrode.

The mode of operation of the device is as follows: At the beginning of the compression stroke the interior pressure causes the valve electrode 10 to be raised, and the semi-globular valve body 10^c to be forced upon its seat. At the same time the waste gases are forced into the space 7 in the interior of the lower part of the sparkers and between the semi-globular part 10^c, and the plate 10^d, so that the fresh gas mixture is not thereby interfered with. After the passage of the igniting spark the valve electrode 10 remains in the raised position during the explosion and the exhaust stroke. At the beginning of the suction stroke the movable electrode drops down by the action of the atmospheric outer pressure, and thereby strikes against the contact ball 9^a, so that by this means the two electrodes are cleaned from any combustion residues. At the same time the gases compressed in the chamber 7, and subsequently thereof the cooling fresh air passes with great velocity through the narrow annular slot between the outer edge of the plate 10^b and the inner wall of the socket 8, thereby preventing the depositing of residues of combustion at these points which would be liable to cause short-circuiting of the sparking plug.

Upon the now following compression

stroke the operation is repeated in the same manner.

The distance of the raised electrode 10^a from the lower stationary electrode 9^a may 5 be adjusted in a very simple manner by rotating the tube 11 inwards or outwards by means of a screw driver. This distance is preferably made equal to the distance between the upper ends of the two tubes 11 10 and 12, so that the length of the sparking gap may be seen from the outside.

For the cleaning of the sparkler it is, for instance, sufficient, without removing the same from the body of the motor cylinder 15 to merely pour benzene or the like into the upper funnel of the tube 11. The sparking plug may also be detached and taken apart in a very simple manner so that any portions which have become unfit for use, may 20 be easily exchanged.

Among the many advantages of a spark plug according to this invention some of the most important are the automatic and permanent cleaning of the electrodes and of 25 the lower portion of the inner wall of the insulating body, the possibility of adjusting the length of the spark gap from the outside, the very convenient fastening of the insulating sockets, the possibility of ex- 30 changing the several constituent parts and of easily cleaning the same. Various changes and modifications both in the construction as well as in the arrangement of parts will suggest themselves to the expert, 35 so as to adapt the device to varying conditions of application, and I wish it to be understood that my invention is not restricted to the particular form of construction herein shown and described by way of 40 example, except as specified in the claims, hereunto appended.

I claim:

1. Electric sparking plug comprising a metal shell, an electrode fixed in the lower 45 end of said shell, an outer metal tube axially disposed in said shell and insulated against

it, an inner metal tube within and in contact with said outer metal tube and an axially movable electrode intermediate the lower end of said inner tube and said fixed electrode, a short non-cylindrical shaft on said movable electrode extending into the lower end of said inner tube, a valve body on said movable electrode adjoining said shaft and adapted to close the lower end 55 of said inner tube and an insulating sleeve surrounding said movable electrode.

2. Electric sparking plug comprising a metal shell, an electrode fixed in the lower end of said shell, an outer metal tube axially 60 disposed in said shell and insulated against it, an inner metal tube within and in contact with said outer metal tube and an axially movable electrode intermediate the lower end of said inner tube and said fixed 65 electrode, a short non-cylindrical shaft on said movable electrode extending into the lower end of said inner tube, a valve body on said movable electrode adjoining said shaft and adapted to close the lower end 70 of said inner tube, an insulating sleeve surrounding said movable electrode and a plate-shaped enlargement on said movable electrode adjoining said valve body.

3. Electric sparking plug comprising a 75 metal shell, a spherical electrode fixed in the lower end of said shell, an outer metal tube axially disposed in said shell and insulated against it, an inner metal tube within and in contact with said outer metal tube and an axially movable electrode intermediate the lower end of said inner tube and said fixed 80 electrode, a short non-cylindrical shaft on said movable electrode extending into the lower end of said inner tube, a valve body on said movable electrode adjoining said shaft and adapted to close the lower end of 85 said inner tube and an insulating sleeve surrounding said movable electrode.

In testimony whereof I affix my signature.

LUDOMIR KORCZYNSKI.
